UNITED STATES PATENT OFFICE.

GEORGE F. TIFFANY, OF NEW YORK, N. Y.

CIGARETTE-CASE.

1,256,953.

Specification of Letters Patent. Patented Feb. 19, 1918.

Application filed April 20, 1917. Serial No. 163,410.

To all whom it may concern:

Be it known that I, GEORGE F. TIFFANY, a citizen of the United States, and a resident of the city of New York, in the county of New York and State of New York, have invented certain new and useful Improvements in Cigarette-Cases, of which the following is a specification.

The present invention relates to cigarette cases of the type adapted to hold a row of cigarettes, arranged side by side, and having a delivery opening, with which coöperates an ejector and a spring-actuated follower, for discharging, at will, through the delivery opening the foremost cigarette of the row.

As far as known, in the devices heretofore in use, the follower is usually associated with guiding means, with which it is in sliding contact. In practice it has been found that the follower is apt to bind, thereby causing much inconvenience, as it is necessary, in order to reestablish the operativeness of the device, to open the cigarette case.

The main object of the present invention is to overcome these difficulties, and to provide a simple and durable construction, that can be manufactured on a commercial scale, or, in other words, one which is not so difficult to produce as to be beyond the reasonable cost of such an article.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

50 Figure 1 is a front elevation of a cigarette case constructed in accordance with this invention, with the foremost cigarette partly pushed out of the case for removal by the user; Fig. 2 is a top plan of this case, its cover being open and partly broken away; Fig. 3 is a side elevation thereof; Fig. 4 is

a section taken on line 4—4 of Fig. 2; Fig. 5 is a section taken on line 5—5 of Fig. 2; Fig. 6 is a top plan view, partly in section, on a larger scale, of a detail of construction; 60 Fig. 7 is a section taken on line 7—7 of Fig. 6; and Fig. 8 is a perspective view of the ejecting mechanism.

In the drawings, the numeral 10 indicates, as an entirety, the body of the box of the cigarette case, which, in the form shown, is a rectangular structure of slightly greater height than the thickness of the cigarettes adapted to be contained therein, and has substantially wedge-shaped edges 11. A cover 12 is hinged to the box to close the same, means being provided for holding the said cover in its closed position, said means consisting, for instance, of a protuberance 13 on the side 14 of the box, which coöperates 75 with a depression 15 in the cover. In parallel relation to the bottom 16 of the box are disposed along the upper free edges of the sides thereof inwardly projecting flanges 17, which are, preferably, made integral with 80 the said sides. Along the longitudinal edges of the box are placed into the same partitions 18, which extend at right angles to the bottom and are throughout their lengths in contact with the said bottom and the flanges 85 17 above mentioned. These partitions are attached to the bottom and flanges in any suitable manner, for instance, by solder. Each of these partitions is provided with a longitudinal slot 19, for a purpose hereinafter 90 to be described. With the end 20 of the box there is made, preferably, integral a flange 21, extending inward in parallel relation to the box bottom and thence downwardly, as clearly shown at 22, at right angles to the 95 said bottom, forming thus, with the bottom, a compartment 23, in which is disposed, as will hereinafter appear, the ejecting mechanism of the cigarette case. A discharge opening 24 is formed in the side 14 of the 100 box adjacent the portion 22 of the end flange above mentioned. The cover 12 has in its free side a cut-out portion 25 in registering position with the discharge opening 24.

105 The flanges 17 hold in place and guide the movement of a follower 26, that is substantially U-shaped in cross-section, and comprises sides 27 that are connected by a web 28. Adjacent each end of the follower there 110 is mounted in the sides 27 thereof a spindle 29, the square ends 30 of which fit into square

holes in the sides of said follower, thereby holding the said spindles against rotation. Upon each spindle is rotatably mounted a pulley 31, provided with peripheral flanges 32, which project through the slots 19 in the partitions 18 into the spaces formed by the said partitions and the box body. In each pulley is formed a recess 33, within which is disposed a spiral spring 34, that is coiled 5 upon the respective spindle 29, and has one of its ends attached to the said spindle, while its other end is fixed to the pulley. A cord or similar flexible means is attached at one of its ends to each pulley, runs over the 10 said pulley and extends into the space formed by the corresponding partition 18 and the box body up to the head 36 of the partition, to which its other end is fastened. 15

20 Within the compartment 23 is disposed an ejecting mechanism, consisting of a plate member 37, having lugs 38 and 39 which extend sidewise in opposite directions, the lug 38 projecting through a slot 40 in the end 20 25 of the box, and the lug 39 through a slot 41 in the flange portion 22 thereof. A spring 42 is fastened to an ear 43 on the plate member 37 and to the side 43' of the box, tending to move the ejecting mechanism toward the 30 said side. The lug 38, arranged outside of the box, constitutes the finger piece of the ejector, and the lug 39, within the box body, the foot thereof. This foot lies normally close to the side 43', as clearly appears from 35 Fig. 2 of the drawings.

The operation of this device is as follows: In filling the box with cigarettes, the cover 12 is swung open, and the follower 26 forced 40 toward the box end 44, the cigarettes being inserted by placing the same, one after the other, into the space between the flange portion 22 and the free transverse ends of the flanges 17, and bringing them toward the follower, which is kept in its retracted position by one hand of the user. With the case loaded and the cover closed, by shifting the ejector endwise toward the discharge opening, the foremost cigarette is projected through the said opening a sufficient distance 45 to be readily grasped by the thumb and the finger and withdrawn. The spring 42 instantly retracts the ejector as soon as released, and returns it to a position wherein it comes into operative relation to the next 50 cigarette of the row which has now become the foremost under the action of the spring-pressed follower. The foot 39 acts as the ejector proper by coming into contact, when being pushed sidewise, with one end of the cigarette. These operations are repeated 55 until the last cigarette has been withdrawn, after which the cover may be opened, the follower retracted and the case reloaded.

It is obvious that, when the follower is retracted for the purpose of loading the case,

the cords are unwound from their pulleys and the spiral springs put under tension, ready to force the follower toward the discharge opening. As the follower moves toward the discharge opening, the cords are rewound upon their respective pulleys. 70

From the foregoing it appears that the pulleys 31 not only serve as the means over which the cords 35 run, and as storing means for the spiral springs 34, but also as guiding 75 means for the follower 26. The guiding is effected by the flanges 32 of the pulleys, which project through the slots 19 in the partitions 18. Moreover, these pulleys, being in rolling contact with the partitions, effectively 80 prevent a binding of the follower in the device.

What I claim is:

1. In a cigarette case, the combination with a box adapted to hold a row of cigarettes 85 arranged side by side and having a discharge opening in one of its sides, partitions within said box adjacent to its sides and extending from one of its ends to said delivery opening, said partitions being provided with longitudinal slots facing each other and the sides of said box having inwardly extending flanges projecting beyond said partitions, a follower in engagement with said flanges, spring-pressed pulleys mounted upon said 90 follower having peripheral flanges seated in said slots, and a cord wound upon each of said pulleys, one end of each cord being attached to a pulley and its other end to the respective partition adjacent said discharge 95 opening, and an ejector operative to force the foremost cigarette of the row endwise through said opening.

2. In a cigarette case, the combination with a box adapted to hold a row of cigarettes arranged side by side and having a discharge opening in one of its sides, partitions within 105 said box adjacent to its sides and extending from one of its ends to said delivery opening, said partitions being provided with longitudinal slots facing each other and the sides of said box having inwardly extending flanges projecting beyond said partitions, a follower in engagement with said flanges, 110 pulleys rotatably mounted upon said follower having peripheral flanges seated in said slots, each pulley being provided with a recess, a spring in the recess of each pulley for putting the same under tension, a cord wound upon each of said pulleys, one end of each cord being attached to a pulley and its other end to the respective partition adjacent 115 said discharge opening, and an ejector operative to force the foremost cigarette of the row endwise through said opening. 120

3. In a cigarette case, the combination with a box adapted to hold a row of cigarettes arranged side by side and having a discharge opening in one of its sides, partitions within said box adjacent to its sides 130

and extending from one of its ends to said delivery opening, said partitions being provided with longitudinal slots facing each other and the sides of said box having inwardly extending flanges projecting beyond said partitions, a follower in engagement with said flanges, two spindles fixedly attached to said follower, a pulley rotatably mounted upon each spindle having peripheral flanges seated in one of said slots, said pulleys being each provided with a recess, a spring in each recess attached to the re-

spective pulley and spindle, a cord wound upon each of said pulleys, one end of each cord being attached to a pulley and its other end to the respective partition adjacent said discharge opening, and an ejector operative to force the foremost cigarette of the row endwise through said opening. 15

Signed at New York, in the county of New York and State of New York, this 26th day of February, A. D. 1917. 20

GEORGE F. TIFFANY.
